(57) CLAIM

The ornamental design for a shirt with a centered pocket, as shown and described.

DESCRIPTION

FIG. 1 is a front perspective view of the shirt with centered pocket, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is bottom plan view thereof; and,

FIG. 8 is another front perspective view thereof, showing the new design in use.

The broken lines shown in the drawings depict a smartphone, which is to show a possible use of the pocket only, and forms no part of the claimed design. Broken lines shown in the drawing also illustrate portions of a shirt that form no part of the claimed invention and are only shown to provide context to the centered pocket's location on a shirt.
